UNITED STATES PATENT OFFICE.

FRANK W. CHATTERSON, OF DETROIT, MICHIGAN.

DESIGN FOR A PORTIÈRE.

46,767.

Specification for Design.

Patented Dec. 15, 1914.

Application filed October 6, 1914. Serial No. 865,886. Term of patent 7 years.

To all whom it may concern:

Be it known that I, FRANK W. CHATTERSON, a citizen of the United States, residing at Detroit, in the county of Wayne and State of Michigan, have invented a new, original, and ornamental Design for Portières, of which the following is a specification, reference being had to the accompanying drawing, forming part thereof.

The figure is a view in elevation of my improved drapery, showing my new design.

I claim:

The ornamental design for a portière, as shown.

FRANK W. CHATTERSON.
